F. R. SKINNER,
PAPER BAG.
APPLICATION FILED AUG. 2, 1919.

1,346,852.

Patented July 20, 1920.

FIG - 1.

UNITED STATES PATENT OFFICE.

FRED R. SKINNER, OF SYRACUSE, NEW YORK, ASSIGNOR OF ONE-HALF TO ERNEST RIPLEY, OF LOS ANGELES, CALIFORNIA.

PAPER BAG.

1,346,852.

Specification of Letters Patent. Patented July 20, 1920.

Application filed August 2, 1919. Serial No. 314,863.

To all whom it may concern:

Be it known that I, FRED R. SKINNER, of Syracuse, in the county of Onondaga, in the State of New York, have invented new and 5 useful Improvements in Paper Bags, of which the following, taken in connection with the accompanying drawings, is a full, clear, and exact description.

This invention relates to certain improvements in paper bags, having a folding flap constituting a closure for the open end thereof, and refers more particularly to means for locking the flap in the closed position and permitting it to be opened, at will, and 15 at the same time serving as a handle by which the bag may be conveniently carried.

The main object is to make the combined lock and handle as an integral part with a minimum waste of stock, or in other words 20 to provide the front side of the open end of the bag with a tongue adapted to pass through the opening in the flap as the latter is folded to its closed position, and to provide said tongue with opposed wings capable of folding within the area of the flap 25 opening and of unfolding beyond the walls thereof, when the flap is closed for locking said flap against accidental opening.

Another object is to provide the tongue 30 with an aperture through which the finger may be readily passed for carrying the bag.

Other objects and uses relating to specific parts of the bag will be brought out in the following description.

35 In the drawings, Figures 1 and 2 are front elevations of a paper bag embodying the features of my invention, the flap being closed in Fig. 1 and open in Fig. 2.

Fig. 3 is a plan of a blank for forming 40 the bag shown in Figs. 1 and 2.

Fig. 4 is an enlarged transverse sectional view taken on lines 4—4 Fig. 1.

As illustrated the blank for forming this bag comprises a rectangular front portion 45 —1— and a back rectangular portion —2— both of substantially the same dimensions and integrally united end to end along a score line —3— so as to fold at said line one upon the other.

50 The back portion —2— is provided along its opposite longitudinal edges with similar integral binding strips —4— adapted to be folded along score lines —5— upon the inner face of the back portion —2— and provided on one side with an adhesive for se-

curement to the adjacent longitudinal edges of the front portion —1— when the latter is folded over upon the back portion, thereby forming a substantially flat paper bag or cache.

The free end of the back portion —2— is provided with a lengthwise extension —6— forming a flap of substantially the same width as that of the body portions —1— and —2— and adapted to be folded along 65 the transverse score lines —7— upon the outer face of the adjacent end —1— for closing the open end of the bag.

The flap —6— is provided with a central opening —8— extending outwardly 70 from the score line —7—, the inner end being straight and registering with said line, while the remaining portion is preferably circular for receiving a tongue presently described, on the adjacent end of the front 75 portion —1—.

The portion of the back —2— and flap —3— immediately surrounding the opening —8— is strengthened by an extra piece of paper or reinforcement —9— adhesively secured to the inner face or flap as shown more clearly in Figs. 2 and 3.

The free end of the front portion —1— is formed with a central tongue —10— extending beyond the end edges thereof, for 85 entering the opening —8—, a portion of said tongue being formed by slits —11— in the main body of the front —1—, said slits being of substantially the same length, but of less length than that of the opening —8—, 90 so as to form locking members —12— partially within the end edge of the portion —1—.

These locking members —12— constitute wings on the opposite longitudinal edges of 95 the tongue —10— and are foldable along the score lines —13— so that when folded the tongue may readily enter the opening —8— when the flap —6— is closed and may then be unfolded upon the front face of the closed 100 flap to hold the latter in its closed position.

The width of the tongue across the wings which are preferably semi-circular, is somewhat greater than that of the opening —8— when the wings are unfolded, although the 105 remaining portions of the tongue are approximately the same or slightly less width than that of the opening.

It therefore follows that in closing, it is simply necessary to fold the wings —12— 110

forwardly toward each other along the score lines —13— which will allow the tongue to readily enter the opening —8—, and as soon as the flap —6— is brought flatwise against the front face of the front portion —1— the wings —12— may be unfolded across the front face of the adjacent portion of said flap to lock the latter in its closed position, the reverse operation of the wings being necessary to release the flap.

The tongue —10— including its wings —12— and also the adjacent portions of the front portion —1— of the bag is reinforced by an extra strip —14— of similar paper adhesively secured to the inner face of the front portion —1— preferably before the latter is adhesively secured to the binding strips —4—.

The tongue —10— is provided with a finger opening —15— thereby producing what may be termed a finger loop, secured to, but preferably integral with the upper end of the front side of the bag and adapted to extend through the opening —8— in the flap —6— when the latter is folded over upon the front face of said front side of the bag, during which operation, the wings —12— are automatically compressed toward each other by the walls of the opening to allow said walls to pass below the lower edges of the wings for interlocking engagement therewith, it being understood that the wings automatically expand for locking purposes when the flap is folded against the front side of the bag.

By attaching the finger loop directly to the upper end of the front side of the bag and passing it through an opening in the flap which is attached to the back side of the bag causes the load to be carried by the front

side through the medium of the loop, thereby preventing any possibility of accidental opening of the mouth of the bag or loosening of the flap when the bag is distended by the contents or load which is of the utmost importance in devices of this character, both from the point of economy in manufacture, rapidity of adjustment for use and safety in confining the contents within the bag when carried by the loop.

50

What I claim is:

A paper bag of the character described comprising a back portion and a front portion united along one end and also along their opposite longitudinal edges, the upper end of the front portion being provided with a finger loop having laterally projecting wings on opposite edges thereof, the back portion being provided with a flap foldable over and upon the front face of the front portion, said flap having an opening for permitting the finger loop to pass therethrough when the flap is folded, said opening being of less width than the transverse width of the finger loop across the wings thereof to permit the latter to interlock with the front face of the flap at opposite sides of the opening when the flap is folded, portions of the wings being formed from portions of the front of the bag below the upper edge of said front and other portions extended above the upper edge of the front and also above the lower edge of the opening in the flap when the latter is unfolded.

In witness whereof I have hereunto set my hand this 30th day of July, 1919.

FRED R. SKINNER.

Witnesses:

HOWARD P. DENISON,
H. E. CHASE.
